UNITED STATES PATENT OFFICE.

JOHN T. LALLY, OF WILMINGTON, DELAWARE.

BOTTLE AND HOLDER FOR CHEMICAL ENGINES.

No. 890,286.

Specification of Letters Patent.

Patented June 9, 1908.

Application filed October 23, 1907. Serial No. 398,738.

To all whom it may concern:

Be it known that I, JOHN T. LALLY, a citizen of the United States, residing in Wilmington, Delaware, have invented certain improvements in Bottles and Holders for Chemical Engines, of which the following is a specification:

My invention relates to certain improvements in chemical fire extinguishers in which the bottle is placed in a holder within the tank and inverted so as to discharge the contents of the bottle into the tank.

One object of the invention is to so construct the bottle holder and bottle that the bottle can be readily placed in the holder or removed therefrom, the bottle not becoming detached when the holder is inverted.

My invention also relates to certain improvements for carrying the bottle and placing it in the holder.

In the accompanying drawings:—Figure 1, is a sectional view through sufficient of a tank to illustrate my invention, showing the bottle and holder in section; Fig. 2, is a view showing the bottle holder and bottle inverted; Fig. 3, is a side view partly in section illustrating the bottle and handled cap; Fig. 4, is a detached perspective view of the bottle holder, and Fig. 5, is a detached perspective view of the bottle.

Referring to the drawings, A is a tank of a fire extinguisher of the ordinary type having a cap a provided with the usual handled stem a' and having a tapered cork a² at its lower end to close the mouth of the bottle when the bottle is in position in the holder. Directly under the opening in the tank is a holder B, having trunnions b in the present instance adapted to bearings in the side walls of the tank. The side b' of the holder is preferably vertical, while the side b² is inclined, as shown clearly in Fig. 1. The bottom b³ of the holder is preferably higher at the side b² than at the side b' and there is a lip b⁴ on the upper edge of the side b' to engage the bottle when the holder is inverted.

D is the bottle which is preferably made of metal although it may be made of any material if desired and this bottle is adapted to fit freely in the holder B and rest upon the bottom, as indicated in Fig. 2. The bottom being higher at one side than the other throws the bottle towards the side b' and the edge of the bottle extends under the lipped flange b⁴. There is an annular flange d extending around the upper edge of the bottle D and this flange

is of such a width that when the holder is inverted the bottle will slide on the holder until the flange d enters the space back of the flange of the lip; the lip preventing the bottle from falling out of the holder.

The space between the lip b⁴ and the opposite side b² of the holder is of sufficient width to allow for the free passage of the bottle when it is to be inserted in the holder or removed therefrom. The bottle has a tapered mouth d' into which the cork a² can be inserted by turning the screw stem a' when the apparatus is in use.

I preferably mount a rubber disk on the bottom b³ of the holder although this is not absolutely necessary and in order to prevent the bottle turning in the holder when the cap E is applied to the bottle or removed from it I slot the holder at f-f, as clearly shown in Fig. 4, and provide the bottle D with lugs d² which enter the slots when the bottle is inserted in the holder. The slots are somewhat larger than the lugs and there is sufficient freedom for the bottle to locate itself in the holder so that a portion of its edge will always be under the lipped flange.

The bottle D contains acid or other suitable material which when discharged into the tank A forms a gas and in order to handle the bottle so that the hands of the person using the same will not come in contact with the acid, I provide a handled cap E having a flange e on which are lugs e' adapted to engage the flange d³ on the neck of the bottle, as clearly shown in Fig. 3. This flange is recessed at d⁴ so that when the handle is turned and the lugs enter the recesses they will be locked owing to the pressure of a spring i upon a plate I which rests upon the end of the bottle and forms a closure for the bottle preventing the escape of the acid or other contents.

In the present instance the plate I has a hollow stem i' which extends into the handle e of the cap E and there is a pin i² fitting in a slot in this stem which limits the movement of the cap. Thus it will be seen that the bottle can be readily carried and placed in the holder with the lugs d² within the slots and the handled cap E can be readily detached by giving it a half turn. The handle is then removed and the cap a secured to the tank and the stem a' turned so that the tapered cork a² will enter the mouth of the bottle closing it so that acid will not spill while the chemical apparatus is going to a fire.

When it is desired to use the apparatus the screw stem is backed off so as to detach the cork. The bottle tilts to the side *d* of the holder and the handle *C* shown by dotted lines in Fig. 1 is turned so as to invert the holder and bottle as illustrated in Fig. 2; there being provided a stop *b* on the outside of the tank *A*, as shown in dotted lines in Fig. 1 to prevent turning of the handle in the wrong direction. The contents of the bottle will be discharged into the tank, but the bottle itself will be held by its flange engaging the flanged lip of the holder. When the contents of the bottle are discharged the handle 15 is turned to its original position and when it is desired to renew the charge the cap *a* is detached from the tank, the handled cap *E* is clamped to the bottle and the bottle detached and another substituted for it when 20 the above operation can be repeated.

I claim:

1. The combination in a chemical fire extinguisher of an open ended bottle holder having a lip, and a bottle for said holder constructed to be engaged by the lip when the holder is inverted under conditions of use, the opening in the holder being of a size sufficient to permit of the unobstructed removal of the bottle without interfering with the lip.
2. The combination in a chemical fire extinguisher, of a bottle holder capable of being inverted having a lip at one side and having an inclined bottom, a bottle adapted to the holder and arranged to rest on the inclined bottom so that the bottle will be forced against the lipped side of the holder, said bottle having a flange adapted to be engaged by the lip of the holder when the bottle is inverted to discharge the contents of the holder.
3. The combination of a pivoted open ended bottle holder having a lip at one side, with a bottle having a flange placed to be engaged by the lip under predetermined conditions, said bottle being of a diameter such as to permit of its unobstructed removal through the opening in the holder, and the parts being so arranged that said bottle will be engaged and held by the lip when the holder is inverted.
4. The combination in a fire extinguisher, of a pivoted holder having a lip at one side and slotted, a bottle having a flange arranged to be engaged by the lip when the holder is turned with the bottle, a lug on the

bottle entering said slot in the holder so as to prevent the bottle turning in the holder.

55

5. The combination of a pivoted bottle holder having a lip at one side, a bottle having a flange arranged to be engaged by the lip when the bottle is turned with the holder, a slot on each side of the holder, a lug on each side of the bottle adapted to rest in the slots, a cap adapted to engage the neck of the bottle and having a spring plate adapted to press against the end of the bottle, the lugs preventing the bottle turning in the holder 65 when the cap is applied.

6. The combination of a bottle for a fire extinguisher having a neck, recessed flanges on the neck, a handled cap adapted to be attached to the holder having a flange, lugs on the flange engaging the flange of the neck of the bottle, and a spring actuated plate carried by the cap and adapted to rest upon the end of the bottle and close it and to hold the lugs in position in the recess of the flanges on 75 the neck of the bottle.

7. The combination in a chemical fire extinguisher, of a tank, a bottle holder mounted on trunnions within the tank, a handle for turning the holder, said holder being straight 80 on one side and inclined on the other and having an inclined bottom, a flanged lip on the straight side of the holder projecting from the upper portion thereof, slots on each side of the holder, a bottle adapted to freely pass 85 into the holder and having a flange at its upper edge arranged to be engaged by the flanged lip of the holder when the two are inverted, lugs on the bottle entering the slots in the holder, said bottle having a flanged neck 90 adapted to be engaged by a handled cap.

8. The combination in a chemical fire extinguisher of a bottle, a holder open at the end sufficiently to permit the passage of said bottle into it, with a projection on one of the 95 parts comprised by the bottle and the holder placed to engage the other part in order to retain the bottle in the holder when the latter is inverted.

In testimony whereof, I have signed my 100 name to this specification, in the presence of two subscribing witnesses.

JOHN T. LALLY.
